CLAIM

The ornamental design for a cap for cosmetic product, as shown and described.

DESCRIPTION

FIG. 1 is a perspective view as seen from the top, front and right side of a cap for cosmetic product showing our new design;

FIG. 2 is a right side elevational view thereof, the left side elevation being a mirror image thereof;

FIG. 3 is a top plan view thereof;

FIG. 4 is a front elevational view thereof, the rear elevation being a mirror image thereof; and,

FIG. 5 is a bottom plan view thereof.
